UNITED STATES PATENT OFFICE

JOSEPH F. CHLADEK, OF NIOBRARA, NEBRASKA

HAY STACKER

Application filed May 7, 1930. Serial No. 450,490.

The invention relates to improvements in material handlers of the type commonly known as hay stackers, although not restricted to this particular field of use.

5 One object of the invention is to generally improve upon the construction shown by my U. S. Patent No. 1,422,667 of July 11, 1922, the improved structure being such as to possess more rigidity for handling heavy 10 loads and to require less expenditure of power.

A further object is to provide a stacker wherein the stacking head on the ends of the conventional vertically swingable arms, is 15 operated by a novel arrangement of levers and standards, serving to equalize the pull throughout the entire upward movement of the load.

Another aim is to provide a stacker of such 20 construction as to reduce the amount of pull upon the operating cable, to a minimum, in turn reducing the distance which the prime mover, whatever it may be, must travel.

Yet another aim is to generally improve 25 upon stacking devices by the provision of one of rather simple, yet durable construction which will effectively accomplish the desired results and can be manufactured and sold at comparatively low cost.

30 A still further object is to provide novel means for supporting the swingable arms which carry the stacking head, when the stacker is to be transported from one place to another, said means being retractible when 35 the stacker is to be operated.

With the foregoing and minor objects in view, the invention resides in the novel subject matter hereinafter described and claimed, description being accomplished by 40 reference to the accompanying drawings.

Fig. 1 is a side elevation showing the relation of parts which exists when the stacking head is lowered.

45 Fig. 2 is a view similar to Fig. 1, but showing the relation of elements when the stacking head is partially raised.

Fig. 3 is a top plan view with the parts related as in Fig. 2.

50 Fig. 4 is a vertical transverse sectional

view taken substantially on line 4—4 of Fig. 1.

Fig. 5 is a side elevation showing the relation of parts when the stacking head is completely raised. 55

Fig. 6 is an enlarged longitudinal sectional view through a number of parts in the relation illustrated in Fig. 5.

Fig. 7 is a perspective view illustrating the two levers hereinafter described. 60

Fig. 8 is a detail sectional view on line 7—7 of Fig. 2.

Fig. 9 is a perspective view illustrating a portion of the base and the swingable standards which are mounted on said base to 65 carry the levers shown in Fig. 6.

The drawings above briefly described may be considered as showing the preferred construction, and while such construction will be herein specifically explained, it is to be 70 understood that within the scope of the invention as claimed, variations may be made.

The base B may well consist of parallel runner-forming sills connected by transverse bars 11, 12 and 13, and suitably braced as 75 at 14, together with a truss structure 15, this truss structure being supported primarily upon the bars 11 and 12 and secondarily by the bracing means 13. The truss structure 15 may be of any desired detail construction, but it preferably embodies two longitudinal sills 16, a longitudinally disposed truss 17 between said sills, and two trusses 18 at the outer sides thereof. 80

The lower ends of two standards 19 are 85 received between the trusses 17 and 18, and a pivot rod, shaft or the like 20 passes through said trusses and said standards to mount the latter for swinging longitudinally of the base B. At opposite sides of the pair of standards 19, are two additional standards 21 forming portions of two A-frames 22, these frames being disposed in a transverse plane. The inner legs of the A-frames, formed by the standards 21, are 90 disposed at the outer sides of the sills 16, while the outer legs of said frames are positioned at the inner sides of bearing blocks 23 which are secured upon the runner-forming sills or the like 10. A second pivot rod 95 100

or shaft 24 passes through the blocks 23 and the sills 16 and through the intervening legs of the A-frames 22, pivotally mounting the latter for swinging longitudinally of the base B. The standards 21 at the inner sides of these A-frames, are received between rollers 25 suitably mounted upon the standards 19, so that a sliding connection is provided between said standards 21 and 19, whereby movement of one pair of standards will effect movement of the other pair.

A suitably trussed lever 26 is fulcrumed between its ends at 27, to the upper ends of the standards 19. A second, bifurcated lever 28 has its furcations 29 fulcrumed at 30 to the upper ends of the standards 21, said furcations straddling one end of the lever 26. This lever end is provided with rollers 31 upon which the furcations 29 rest, establishing a slidable connection between the intermediate portion of the lever 28 and one end of lever 26. Preferably, this lever 26 is provided with guards 32 at the outer ends of the rollers 31 to slidably engage the outer sides of the furcations 29. Lever 28 extends toward the receiving end of the stacker and is connected by lift rods or the like 33 with longitudinal arms 34, said arms being pivoted to the base B and provided with a stacking head 35. The end of lever 26 remote from the rods or the like 33, is provided with a sheave 36 and with a cable anchor 37. A second sheave 38 is carried by links 39 which are connected with the lower portions of the standards 21. A third sheave 40 is mounted between the sills 16 at the end thereof toward the delivery end of the stacker, and mounted on the transverse bar 13 at said end of the stacker, is an appropriate cable guide 41. An operating cable 42 is anchored at one end to the anchor 37 and is trained around the sheaves 38, 36 and 40, the free end of the cable being passed through the guide 41 to be operated in the usual way to effect raising and lowering of the stacking head 35.

Preferably, the inner ends of the arms 34 are provided with downwardly projecting blocks or the like 43 through which a shaft 44 passes to pivotally connect said arms with the base B. This construction also provides an off-center pivotal mounting for the arms 34, with the result that before said arms are completely raised to vertical positions, the center of gravity of the stacking head 35 and its load, will pass a plane extending through the pivot 44, causing the arms 34 and stacker 35 to complete their stacking movement by gravity. The movement of these parts in stacking direction, may be limited by cables or the like 45 which are connected at one end with the arms 34, the other ends of said cables being connected with a shock absorbing device 46 which is anchored at 47 to the crown of the truss 17.

The anchor 47 is preferably on the upper end of a strut bolt 48, the lower end of this bolt being passed through a plate or the like 49 which extends under the sills 16 and may assist in supporting the trusses 18, as seen in Figs. 6 and 8.

For the purpose of supporting the arms 34 and stacking head 35 above the ground when the machine is being drawn from one place to another, I provide the bars 50 which are shown most clearly in the lower portion of Fig. 8. These bars are pivoted at 51 upon the bar 11 so that they may swing inwardly to the full line positions of Fig. 8 or outwardly to the dotted line positions thereof. When the machine is operating, the bars 50 are in their inwardly swung positions, but when the machine is to be transported, these bars are swung outwardly and may then serve as supports upon which the arms 34 rest, holding these arms and the stacking head 35 considerably above the level of the ground.

The stacking head 35 is loaded when the parts are in the relative positions shown in Fig. 1. A pull upon the cable 42, now causes swinging of the levers 26 and 28 and swinging of the standards 19 and A-frames 22 toward the discharge end of the stacker, as seen in Fig. 2. The sliding connection between the lever 26 and the lever 28 is of course the instrumentality for imparting movement to the latter and this lever 28 pulls upon the connections 33 to upwardly swing the arms 34 and their stacking head 35. By the time the parts have moved about to the maximum, as seen in Figs. 5 and 6, the arms 34 have swept past their dead center positions and the load is discharged in the usual way. As the raised arms 34 reach their final raised positions, the cables or the like 45 tighten and stress the spring of the shock absorber 46, with the result that this spring acts to re-swing the arms 34 past dead center to allow them to return by gravity, thereby causing return of the other parts to their normal positions, as slack is created in the pull cable 42.

It will be seen from the foregoing that I have made novel provision for carrying out the objects of the invention, and attention is again invited to the fact that within the scope of said invention as claimed, variations may be made.

I claim:

1. A stacker comprising a base, longitudinal arms pivoted to said base and having a stacking head, a standard pivoted to said base to swing longitudinally thereof, a second standard pivoted to said base to swing longitudinally thereof, a sliding connection between the two standards whereby swinging of one will swing the other, a longitudinal lever fulcrumed between its ends to the upper end of the first named standard,

a second longitudinal lever fulcrumed at one of its ends to the upper end of said second standard and extending therefrom toward the receiving end of the stacker, lift connections between the other end of said second lever and the aforesaid arms, a sliding connection between one end of the first named lever and the intermediate portion of said second lever, and means connected with the other end of said first named lever for drawing said end toward the base.

2. A stacker comprising a base, longitudinal arms pivoted to said base and having a stacking head, a standard pivoted to said base to swing longitudinally thereof, a second standard pivoted to said base to swing longitudinally thereof, a sliding connection between the two standards whereby swinging of one will swing the other, a longitudinal lever fulcrumed between its ends to the upper end of the first named standard, a second longitudinal lever fulcrumed at one of its ends to the upper end of said second standard and extending therefrom toward the receiving end of the stacker, lift connections between the other end of said second lever and the aforesaid arms, a sliding connection between one end of the first named lever and the intermediate portion of said second lever, one sheave on the other end of said first named lever, a second sheave on said second standard near the lower end of the latter, a third sheave on the base spaced toward the delivery end of the stacker from said standards, and an operating cable trained around said sheaves and anchored at one end.

3. A stacker comprising a base, longitudinal arms pivoted to said base and having a stacking head, a standard pivoted to said base to swing longitudinally thereof, two A-frames disposed in a transverse plane and positioned at opposite sides of said standard, the lower ends of said A-frames being pivoted to the base on a transverse axis, sliding connections between said standard and said A-frames, a lever fulcrumed between its ends to the upper end of said standard, a bifurcated lever having its ramifications pivoted to the upper ends of said A-frames, said bifurcated lever extending toward the receiving end of the stacker, lift connections between said bifurcated lever and the aforesaid arms, a sliding connection between the intermediate portion of said bifurcated lever and one end of the first named lever, and means connected with the other end of said first named lever for drawing it toward the base.

40 In testimony whereof I have hereunto affixed my signature.

JOSEPH F. CHLADEK.
